UNITED STATES PATENT OFFICE.

EDWIN M. MOHRMAN AND CHARLES R. McNIECE, OF CLEVELAND, OHIO, ASSIGNEES
TO THE HYDRAULIC PRESSED STEEL COMPANY, OF CLEVELAND, OHIO, A COR-
PORATION OF OHIO.

CONCRETE FORM AND SUPPORT FOR THE SAME.

Application filed August 16, 1919. Serial No. 318,033.

To all whom it may concern:

Be it known that we, EDWIN M. MOHRMAN and CHARLES R. McNIECE, citizens of the United States, residing at Cleveland, in the county of Cuyahoga and State of Ohio, have invented a certain new and useful Improvement in Concrete Forms and Supports for the Same, of which the following is a full, clear, and exact description, reference being had to the accompanying drawings.

This invention relates generally to concrete forms and more particularly to the supporting means for such forms.

The object of the invention is to provide a simple construction of support for the concrete form and whereby great economy is had in the use of shoring; and another object is to provide a novel form of support for the forms or pans which support is of such a nature that the forms or pans can be quickly and easily removed without disturbing the support as a whole and a still further object is to provide a combination form of support capable of use in connection with either the arched or slabbed form of pan.

With these objects in view, and certain others which will become apparent as the description proceeds, the invention consists in the novel features of construction, combination, and arrangement, all of which will be fully described hereinafter and pointed out in the claims. In the drawings forming a part of this specification Fig. 1 is a sectional perspective showing the practical application of my invention; Fig. 2 is a detail sectional view showing the adjacent edges of a pair of forms together with the spacer and supports for said spacer and forms; Fig. 3 is a side elevation of said parts; Fig. 4 is a modified form of supporting arm; Fig. 5 is a sectional view showing the application of our invention to the slabbed form and Fig. 6 is a view illustrating the manner of bridging the space between two adjacent forms.

In carrying out our invention we employ sheet metal forms which may be arched as shown at 10 in Figs. 1 and 2 or flat as shown at 11 in Fig. 5. In both instances the edges of the forms are flanged as shown at 12. The forms are arranged with their flanged edges in parallel relation and resting upon the flanged edges is a sheet metal spacing

strip 13 rigidly secured to a strip of wood 14, the metallic spacing strip being of sufficient length to serve as a spacer for a considerable number of forms arranged end to end and it will be noted that the sheet metal spacing strip 13 rests upon the flanged edge and the wooden strip 14 rests between said flanged edges and in this manner the flanged edges of the forms are spaced apart the proper distance and the bottom of the mold is provided which will prevent the escape of cement or concrete when the same is poured upon the assembled forms as most clearly shown in Fig. 1. The spacer is supported upon a stringer 16, said stringer in turn resting upon the beam 17 which beam is supported by any suitable form of shoring 18. It will be noted by reference to the drawing that one beam 17 is sufficient to support a considerable number of stringers 16 and that a limited amount of shoring will be necessary to support the beam 17. By this arrangement great economy in shoring is obtainable. In order to support the edges of the forms or pans in engagement with the spacers we provide supporting members 19 which are preferably in the form of offset metal arms pivotally connected at 20 to a stirrup 21 which straddles the stringer 16 and which can be placed at any desirable point upon said beam. The supporting arms are of such length and shape that when turned up they will engage the edge of the band and form the proper support for the same and hold the flanged edge in engagement with the spacer and in order to prevent dislocation of said arms a fastening bolt or pin 22 can be passed through an opening 23 in the lower end of the arm into the stringer thereby prevent any movement of said arm. After the cement or concrete has been poured and permitted to set for a short period the pans can be removed provided the molded body is supported at definite intervals, such as at the base of the beam portion and it is with the object of quickly removing the pans and still providing the proper support for the molded structure that we have designed the present type of support; and it will be readily seen that it will be only necessary to withdraw the locking pins 22 and turn down the arms 19 to release the pans and all of which can be accomplished

without disturbing the central support beneath the spacer and the beam portion of the floor or ceiling.

Inasmuch as the pan supporting arms are connected to the stirrups which can be placed at any point upon the stringer it is obvious all of the supporting parts will be kept in their proper assemblage form and consequently there will be no loss of time in getting together the various coacting elements which go to make up the support. In the slab type of form shown in Fig. 5 a suitable truss 23 may be provided if desired to give the necessary strength to support the central portion of the slab. In Fig. 6 we have shown one method of bridging the space between the two forms arranged end to end and spaced slightly apart, the bridging piece being shown at 24 supported upon a stringer 25 which in turn may be supported in any suitable manner, the ends of the bridging piece 24 resting upon the end portions 26 of the form or spacer and preferably spacer. From the above description taken in connection with the accompanying drawings it will be seen that we provide a novel construction of concrete form comprising pans and fillers adapted to cooperate with one another and that in connection with such pans and filler we provide a novel construction of support of such a nature that those portions which support the pans or forms can be quickly and easily moved to release the forms and without disturbing the support as a whole; and it will also be seen that by means of a support of this nature great economy in shoring can be had inasmuch as this form of support is capable of use upon longitudinal stringers which can be supported upon a limited number of transverse beams requiring a minimum amount of shoring.

Having thus described our invention, what we claim is:

1. The combination with a pair of forms, of means engaging the adjacent edges of said forms, and spacing them apart, a sup-

port for said spacing means, and means pivotally connected with said support and adapted to support said forms and hold the edges thereof in engagement with the spacing means.

2. The combination with a pair of forms having flanged edges, of means engaging said flanged edges and spacing them apart, a support for said spacing means, said support having means pivotally connected therewith for supporting the edges of the forms.

3. The combination with a series of forms arranged end to end, and a second series of forms arranged end to end, of means common to all of said forms engaging their adjacent edges and spacing them apart, a support for said common spacing means, and movable devices pivotally connected with said support, for separately engaging and supporting the several forms.

4. The combination with a pair of forms, of means engaging the edges of said forms and spacing them apart, a support for said spacing means, and means pivoted to said support and adapted to engage the edges of said forms, said pivoted means being movable without disturbing the support, whereby said forms can be released.

5. The combination with a pair of forms, of means engaging the adjacent edges of said forms and spacing them apart, a support for said spacing means provided with pivoted means for supporting the edges of said forms and means for locking said form supports.

6. The combination with a suitable support, of a spacer arranged thereon, a pair of forms having their lower edges in engagement with said spacer and means pivotally connected to the support and adapted to engage the lower edges of the forms and hold them in operative position with said spacer.

In testimony whereof, we hereunto affix our signatures.

EDWIN M. MOHRMAN.
CHARLES R. McNIECE.
